(57) **CLAIM**

We claim the ornamental design for a display screen with an animated graphical interface, as shown and described.

DESCRIPTION

FIG. 1 is a front view of a first image in a sequence for a display screen with an animated graphical interface, according to a first embodiment;

FIG. 2 is a front view of a second image in the sequence according to the first embodiment;

FIG. 3 is a front view of a third image in the sequence according to the first embodiment;

FIG. 4 is a front view of a first image in a sequence for a display screen with an animated graphical interface, according to a second embodiment;

FIG. 5 is a front view of a second image in the sequence according to the second embodiment;

FIG. 6 is a front view of a third image in the sequence according to the second embodiment;

FIG. 7 is a front view of a first image in a sequence for a display screen with an animated graphical interface, according to a third embodiment;

FIG. 8 is a front view of a second image in the sequence according to the third embodiment;

FIG. 9 is a front view of a third image in the sequence according to the third embodiment; and,

FIG. 10 is a front view of a fourth image in the sequence according to the third embodiment.

In the first embodiment, the appearance of the transitional image sequentially transitions between the images shown in FIGS. 1 through 3. In the second embodiment, the appearance of the transitional image sequentially transitions between the images shown in FIGS. 4 through 6. In the third embodiment, the appearance of the transitional image sequentially transitions between the images shown in FIGS. 7 through 10. The process or period in which one image transitions to another image forms no part of the claimed design.

The outer broken line rectangle showing the display screen illustrates portions of the article of manufacture, and forms no part of the claimed design. The broken lines shown in FIGS. 1-10 show portions of the display screen with an animated graphical interface that form no part of the claimed design.
